The ornamental design for a luminaire, as shown and described.

DESCRIPTION

FIG. 1 is a front perspective view of a luminaire according to our design;

FIG. 2 is a right elevational view thereof;

FIG. 3 is a left elevational view thereof;

FIG. 4 is a top elevational view thereof;

FIG. 5 is a front elevational view thereof;

FIG. 6 is a bottom elevational view thereof; and,

FIG. 7 is a rear elevational view thereof.

The luminaire is shown with a symbolic break in its length. The appearance of any portion of the article between the break lines forms no part of the claimed design.

The pairs of closely adjacent, spaced jagged broken lines in the drawings form no part of the claimed design and the portions between such pairs of jagged broken lines are broken away to disclose indeterminate length. Portions of the design that may be visible between the jagged lines have been removed for clarity.
